UNITED STATES PATENT OFFICE.

EBEN RAY PACKER, OF NEW ROCHELLE, NEW YORK.

RAILWAY SNOW FLANGER.

Application filed June 10, 1919. Serial No. 303,143.

- This invention relates to improvements in the construction and arrangement of snow removing devices for use with railway cars or locomotives and consists particularly in improvements in the constructing of snow flangers of the type now generally in use and illustrated in prior patents to me Nos. 1,057,084 of Mar. 25, 1913 and 1,162,096 of Nov. 30, 1918.
- 10 The present invention is designed particularly with a view to provide an improved and substantial construction which will operate in an improved manner and will possess features of advantage over flanger constructions as heretofore proposed. To this end my improved flanger construction embodies features of arrangement and mode of operation which contribute materially to the effectiveness and insures the positive operation of the lifting means for the elevation of the flanger as required when passing over a crossing or switch. With respect to the latter feature a particularly important feature of my present invention resides in the 15 employment of plural and independently operating means operative to elevate the flanger clear of obstructions so as to eliminate or reduce to the minimum the liability of damage resulting from contact with obstructions.
- 20 My improved construction insures against damage resulting from the failure or inadequacy of one of the lifting forces and correspondingly a more reliable operation is insured and the factor of safety is increased.
- 25 To effect the lifting operation I desirably employ means operative by fluid pressure such as steam or air under the control of an operator and also means, such as springs, adapted normally to elevate the flangers sufficient to clear obstructions and when it is desired to depress the flanger into its operative position the action of the fluid pressure is reversed and employed to overcome the 30 lifting action of the springs. By the use of my improved arrangement, employing independently acting lifting means, not only is the danger from failure to elevate reduced but the combined forces acting upon the flanger will operate more responsively in the lifting operation and will therefore be more effective to overcome resistance resulting from the pressures and weight of snow against the flanger elements.
- 35 Other important features of my present invention consist of a flanger construction of improved design adapted for double
- track use and effective to discharge the snow all upon one side of the road bed and further adapted to clear the snow or ice from between the rails and in close proximity to the road bed. The latter feature is important in clearing away the crust of snow and ice from the centre of the track which tends to accumulate and build up together with cinders and coal from drippings from the rolling stock. Other valuable features as herein disclosed consist of improvements in the manner of supporting the flangers upon the trucks or upon the body of the vehicle so as to give rigid and substantial support thereto and further in an improved arrangement whereby upon encountering excessive obstructions such as for instance boulders carried upon the road bed by snow slides, the flangers shall be so supported that the excessive stresses shall not be transmitted to the cylinders or operating parts thereof and in consequence the damage from such source will be inconsequential. The feature last referred to is also of value in adapting my improved flanger construction for use in the spreading of ballast or sand upon the road bed.
- 40 The foregoing features and other advantages of my present invention over the prior art structures will be readily understood by reference to the accompanying drawings and the following more detailed description. Referring to the drawings wherein like reference characters are applied to the corresponding parts in the several views.
- 45 Fig. 1 is a view in front elevation illustrating an approved embodiment of my invention wherein oppositely arranged flangers are employed.
- 50 Fig. 2 is a plan view of the construction of Fig. 1.
- 55 Fig. 3 is a view thereof in side elevation.
- 60 Fig. 4 is an enlarged vertical sectional view illustrating in detail the lifting cylinder construction and showing the parts in their relative position when the flanger is depressed or in operating position.
- 65 Fig. 5 is a view partly in elevation and partly in central vertical cross section of the parts illustrated in Fig. 4 and illustrating the relative position of the parts when the flangers are elevated; said Fig. 5 being taken at right angles to Fig. 4.
- 70 Figs. 6, 7 and 8 are views showing a suitable modified form of flanger construction of my invention adapted to clear the entire

space between the rails, of which Fig. 6 is a front elevation, Fig. 7 a plan view and Fig. 8 a view in side elevation illustrating some of the parts in section.

5 Figs. 9 and 10 illustrate a further desirable modification of my invention embodying the features thereof in an improved type of flanger adapted for double track systems and operative to throw snow entirely to the 10 one side and also to clear the full space between the tracks. Of these Fig. 9 is a plan view and Fig. 10 a view in side elevation.

Figs. 11 and 12 illustrate a further desirable embodiment and modification of my 15 invention wherein the flanger element is supported by suitable connections from above the lifting cylinders; the views showing the same in side elevation and in front elevation respectively.

20 Fig. 13 is a view in side elevation illustrating my improved flanger construction embodied in a plow construction.

Fig. 14 is a similar view illustrating the 25 combined use in a snow plow of the flangers of the types illustrated in Fig. 1 and Fig. 9 so as to thoroughly clear the road bed throughout the entire width thereof.

In the specific application of my invention as shown in Figs. 1 to 3 inclusive an 30 arrangement is illustrated wherein flanger plates are operatively related to each of the rails and the supporting and operating means therefor are suspended from a car body desirably by attachment to the forward bumper beam or other supporting member positioned in advance of the forward truck of the car or vehicle. It will be understood that the specific manner of support may be variously modified in accordance 35 with the particular installations and as desired the flanger may be supported upon the car bodies or directly upon the car trucks and in either case I preferably employ the general type of guiding support for the 40 flangers as illustrated in my prior Patent #1,057,084 hereinbefore referred to. Accordingly I have shown the members for supporting the various parts of my device consisting of oppositely arranged main supporting plates 2, 2 which are vertically positioned and which may be varied in form 45 to accommodate them for connection with various types of car bodies or trucks depending upon the particular installations. 50 These supports 2 as indicated are secured in position by means of angles 3, 3 and 4, 4 bolted to the forward or bumper beam 5 of the car body. The supporting members or plates 2, 2 are provided each with a vertical or substantial vertical slot 7, the slots 55 of the respective supporting plates being oppositely positioned and adapted to act as guide slots to control the vertical movement of the flanger elements as now to be described.

Fitting within the slots 7, 7 there is arranged a cross bar 8 which is a carrier member for the respective flangers or flanger plates f. The flangers f are formed of suitable contour with notches 10 formed in their lower edges to provide clearance for the tops of the rail heads and thereby permit the lower edge of the flanger upon opposite sides thereof to extend below the rail heads. The flangers are also supported at 75 a suitable angle to properly deflect the snow and as shown may desirably be secured directly to the carrier bar. For the latter purpose the extremities 11, 11 of the bar 8 may be bent rearwardly at a suitable angle 80 and the outer ends of the flanger plates f may be bolted or otherwise secured thereto. At their inner ends the flanger plates f are secured to the carrier bar 8 by means of suitable brackets 13, 13 secured to the respective members. To coact in properly guiding the movement of the carrier bar 8 suitable guide bars 14 are attached to the carrier bar 8 immediately adjacent to the supporting plates 2 and positioned to engage the outer faces thereof to prevent lateral movement of the carrier bar 8 and the flanger supported thereby. Rigidly secured to the supporting plates 2 there is provided a supporting cross bar 15 having its end portions rearwardly extended and bolted to the supporting plates 2, 2, which are thus connected thereby. As indicated the cross bar 15 is arranged on a plane below that of the carrier bar 8 so that the latter in its lowermost position will bear upon the rearwardly directed end portions 16, 16 of the supporting bar 15. By reason of this relation of the carrier bar 8 and cross bar 15 the latter acts as a lower stop or bearing support for the carrier bar 8 and the flangers attached thereto and is so positioned as to determine the proper spacing of the flangers from the rails when the latter assume their lowered or operating position as indicated in Figs. 1 and 3. The slots 7, 7 are suitably elongated vertically to permit of the carrier bar 8 moving upwardly therein sufficiently to elevate the flangers f so as to pass over obstructions such as crosses and switches with adequate clearance. In so far as described the supporting parts are generally similar to the disclosure of my prior patent aforesaid.

In accordance with an important and characteristic feature of my present invention I have devised an improved arrangement to effect the lifting or elevating of the flangers from their operating position as is required when passing over crossings, switches or other obstructions and when the flangers are not in use. A particularly important feature of my present improvement consists in the employment of plural and independently operative means for elevating the flanger by the use of which the factor of

safety is materially increased. As will be readily appreciated the effectiveness of the lifting means is a factor of the greatest importance to insure against damage or destruction of the flangers and further danger of derailment in consequence thereof and further that the lifting operation must at times be accomplished when there is considerable resistance by reason of pressures of snow and ice to which the flangers are subjected.

In my improved construction I desirably employ as one source of lifting power a fluid pressure such as steam or compressed air which is under the control of the operator and operates to exert a lifting force to raise the flangers and may be reversed and operated to depress the flangers into operating position. In addition I desirably employ a suitable arrangement of compression springs operative normally to elevate and sustain the flangers in a position to clear obstructions. The latter means will thus be effective to elevate the flangers when the fluid pressure is shut off and the flangers not in use and it is arranged that when the flangers are to be used that they shall be depressed into operative position against the influence of the springs by means of the fluid pressure. To this end, in the construction as disclosed oppositely arranged cylinders 20, 20 are secured to the carrier bar 8 as indicated and fitted within the cylinders as best shown in Figs. 4 and 5, pistons 21 are arranged and piston rods 22 are connected thereto by means of clamping nuts 23, 23. The piston rods as shown are provided at their lower ends with bearing members 24 secured upon the rigid supporting bar 15 whereby the piston 21 will be rigidly supported and held and the cylinder 20 attached to the carrier bar 8, is movable with relation thereto.

In accordance with my improved arrangement the cylinder 20 is arranged to be operated in both upward and downward direction under pressure by means of any suitable fluid pressure, for instance steam or compressed air, and under control of the operator by means of a suitable valve not shown and introduced in the cylinder either through the ports 24' above the piston or through ports 25 below the piston to operate respectively to raise or lower the cylinders and the flangers connected therewith. Exhaust ports 26, 27 communicate with the cylinder chamber above and below the piston 21 are indicated. The intake ports 24', 25 are connected by suitable pipes 28 and flexible connections 29 to a suitable source of supply and the discharge or exhaust ports 26, 27 are similarly connected by pipes 30 and flexible connections 31 to a suitable controlling valve in the usual manner as will be readily understood. As indicated the piston

is provided with the usual expandible ring 33 and packing washer 34 and the cylinder chamber is sealed in the usual manner by means of suitable packing 35 and secured in position by means of a gland 36 bolted to the lower wall of the cylinder.

The second and independently operated means for raising the cylinder may consist of compression springs 38 fitted within the upper portion of the cylinders and bearing upon the upper side of the piston and the top wall 39 of the cylinder thereby normally to raise the cylinder into its elevated position as shown in Fig. 5, the strength of these springs being proportioned to effect this lifting operation normally to elevate the flangers to clear obstructions when the fluid pressure for depressing the cylinder is cut off.

As will be readily understood from the foregoing disclosure, the operation of my improved flanger will be that under normal conditions of disuse the compression springs 38, when the fluid pressure is shut off or not connected, will elevate the flangers clear of obstructions and accordingly prevent damage thereto. When in use the fluid pressures introduced in the intake ports 24' will depress the flangers into operating position against the influence of the springs 38 and upon approaching an obstruction reversal of the fluid pressure to enter the cylinders through intakes 25 will exert a lifting force to co-act with that of the springs 38 to quickly and effectively raise the flangers. In the latter instance the dual source of power cooperating to raise the cylinder is particularly valuable and desirable in that the one source compensates for any deficiency or failure of the other and further overcomes resistance which would at times be excessive were but one source of power employed. In consequence reliability in the proper operation is insured and danger reduced to the minimum degree. The foregoing features of my invention are further valuable in adapting my improved flangers for use in the spreading of ballast or sand or for the removal of sand from the road bed which in certain localities is encountered owing to severe sand storms.

While I have described an approved embodiment of the aforesaid features of my invention it will be understood that they may be variously modified in form and arrangement without departing from the broader features thereof. For instance while I have shown the cylinders as immovable and the flangers operatively connected therewith and the pistons rigidly supported it will be readily understood that their relations may be reversed, that is the pistons may be the movable elements and connected to the flangers, with the cylinders immovably sup-

ported. An arrangement of this character is hereinafter described in connection with a suitable modified form.

In Figs. 6, 7 and 8 I have illustrated a desirable modification of the features of my present invention wherein the flangers *f* are suitably modified in form to operatively extend across the entire space between the rails. The form as here illustrated is adapted particularly for single track use and the flanger elements or plates *f* are secured to a reenforcing or backing bar 40 secured to the carrier bar 8 by the bracket 13 heretofore described. The bar 40 is angular in form and has secured thereto a bracing rod 41. The flanger plates have inward extensions 42, 42 whereby they form a combined plow and flanger construction adapted to remove the snow from the entire area between the rails and to deflect it to both sides from the central portion thereof. In its other features of construction the modification of Figs. 6 and 8 is shown generally similar to the application of the features of my invention first described.

Referring to Figs. 9 and 10 I have there illustrated a further desirable modification in an improved construction specially adapted for double track railways and wherein the flanger elements are formed to deflect the snow and ice entirely to one side and further to clear the snow from the entire area between the rails. As here disclosed the opposite flangers and the intermediate plow portion 45 may be formed as a continuous plate secured to a backing member or bar 46 bolted to the carrier bar 8 at its opposite end portions and to intermediate brackets 47 affixed to the carrier bar 8 as shown. In this embodiment of my invention I have shown the carrier bar 8 suitably supported in inclined relation to the car body and as shown the supporting plates 2 and cylinder supporting rod 15 are correspondingly arranged in inclined relation. To give adequate backing support to this type of flanger in addition to the supporting plates 2 at the opposite sides of the car body, intermediate and similar plates 48 are employed as indicated whereby substantial support is given to the flanger throughout its entire length whereby it may successfully remove ice and other accumulations from between the track rails.

In Figs. 11 and 12 I have illustrated a further modified construction of my improved flanger embodying further features of my invention. In the arrangement as there shown the cylinders 20 of the fluid pressure lifting means are rigidly supported and the pistons 21 are the movable members thereof. The cylinders, as illustrated, are attached to a supporting cross bar 52 carried by brackets 53 secured upon the upper surface of the opposite longitudinal frame

beams 54 of the car body. The flanger *f* as shown is generally similar to that illustrated in Figs. 6 to 8 and is secured to the carrier bar 8, the latter being vertically shiftable within guide slots formed in the opposite supporting plates 2 in the manner heretofore described. The supporting plates as here indicated are of suitable form to be carried by the car truck by being directly attached thereto.

As illustrated the piston rods 22 in the form here illustrated extend upwardly from the cylinders and are formed with connecting yokes 24 which receive and support a lifting bar 55 which in turn is suitably connected to the carrier bar 8 whereby when the lifting bar 55 is raised by the pistons the flanger will be correspondingly elevated. The connections between the lifting bar 55 and the carrier bar 8 desirably comprise yoke members 57, 57 connected to the bar 55 and at their lower ends being pivotally connected at 58 with depending links 59; the latter being connected at their lower ends directly to the carrier bar 8 by means of pivot pins 60. The supporting connections thus afforded are such as to permit of lateral shifting in the relation of the flangers to the supporting cylinders as will occur where the flangers are supported upon the trucks and the lifting cylinders upon the car body. This co-relation of the respective parts is desirable in properly supporting the flangers in locations where the cylinders may not conveniently be carried upon the forward bumper beam upon the car body.

An important advantage resulting from the improved construction as illustrated in Figs. 11 and 12 is that the flangers are so supported that in the event of coming into contact with obstructions such as large boulders the damage would be limited to the flanger and its immediate support and would not be transmitted to the lifting means or cylinders and the supports of the latter.

The foregoing is an illustration of one of the various modifications in form and arrangement in which the features of my invention may be embodied. In Figs. 13 and 14 I have illustrated somewhat diagrammatically further applications of my improved flanger construction wherein the same is combined in an approved manner with a desirable form of snow plow. As illustrated in Fig. 13, 65 indicates a snow plow which may be of suitable contour and desirably formed of sheet metal suitably supported upon a carrying vehicle or car 66 in advance of the forward truck 67 in the usual manner. In accordance with my invention I may desirably support my improved flanger upon the forward bumper beam 68 of the car body.

As illustrated the flanger may desirably

be of my improved form as illustrated in Figs. 1 to 3 and operable in the improved manner as heretofore described; the flanger being positioned forward of the truck of the 5 plow car and intermediate of said truck and the nosing portion of the plow proper. However, as will be readily understood my improved flanger may be otherwise situated so as to cooperate with the plow, for instance as shown in dotted lines at 69 the 10 flanger and its cooperating lifting means may be located to the rear of the forward truck with the advantage that the flanger would not remove from the rails the usual 15 signal torpedoes before the forward wheels could pass thereover.

In Fig. 14 I have illustrated a further desirable installation of my improved flangers combined with a snow plow in the manner described wherein 65 indicates the plow proper which may be of a standard or desirable form. Mounted upon the bumper beam 68 there is illustrated the improved 20 flanger of the type illustrated in Figs. 1 to 3 and operative to deflect the snow and ice from the region immediately adjacent to the rail. In addition thereto there is shown at 25 70 a second flanger plow suitably supported to the rear of the forward truck 67 and of 30 the type illustrated in Figs. 9 and 10 hereinbefore described. As will be readily seen the rearwardly arranged flanger plow will be operative to deflect the snow and ice entirely to one side of the track and will remove any accumulations of snow and ice 35 from the entire area between the rails.

While I have described and shown modified forms of my invention it will be understood that the features thereof may be otherwise varied in form and arrangement without departing from scope of the invention. It is therefore intended that all matter contained herein shall be interpreted as illustrative and not in a limiting sense.

I claim:

1. In a device of the character described, the combination of a carrier vehicle, oppositely positioned supporting members connected to the vehicle and provided with oppositely positioned guide ways, a carrier bar fitted within the guide ways and capable of vertical movement therein, flanger plates supported at the opposite sides upon the carrier bar, operating means for the flangers comprising motors positioned adjacent to the opposite sides of the carrier bar, said motors comprising cylinder and piston members, one of said members being suitably supported to be structurally rigid and the other of said members being movable with relation thereto, said motors being adapted to be actuated by fluid pressures in opposite directions, connections between the movable members of the motors and the carrier bar whereby motion imparted to the former will be transmitted to the latter to elevate or depress the flanger plates and compression springs incorporated in the motors and operative normally to elevate and sustain the flangers and proportioned to be yieldable 70 under the action of the fluid pressure in one direction for depressing the flangers into operative position, substantially as described.
2. In a device of the character described, 75 the combination of a carrier vehicle, oppositely positioned supporting members suitably supported thereon, said supporting members being provided with co-acting guide ways, a carrier bar fitted within the 80 respective guide ways and capable of vertical movement therein, flanger deflecting plates supported upon the opposite end portions of the carrier bar to operate adjacent to the rails, a supporting bar positioned below the plane of the carrier bar rigidly supported upon the supporting members and forming a lower bearing stop for the elevating bar, operating means for the flanger plates comprising oppositely positioned motors 85 consisting of cylinder and piston members, one of said members being immovably supported upon the supporting bar and the other of said motor members being movable with relation thereto, connections from the 90 movable motor members to the carrier bar whereby the latter is elevated or depressed thereby, said motor being adapted to be actuated by a fluid pressure for both elevating and depressing the carrier bar and compression springs incorporated in the motors and operative normally to elevate the carrier bar and flangers attached thereto, substantially 95 as described.
3. In a device of the character described, 100 the combination of a carrier vehicle, oppositely arranged supporting members provided with co-acting substantially vertical guide ways, a carrier bar transversely arranged and fitted to said guide ways, guide 105 shoulder elements provided on the carrier bar to engage the supporting members to prevent transverse shifting of the carrier bar, flanger deflecting plates supported upon the opposite ends of the carrier bar and positioned to operate adjacent to the rails, a supporting bar attached to the supporting members and positioned beneath the carrier bar to provide a lower stop bearing therefor, operating means for the carrier bar comprising 110 oppositely positioned motors consisting of cylinder and piston members, said pistons being rigidly supported upon the supporting bar and said cylinders being movable with relation thereto and connected to the carrier bar whereby the latter and the flanger plates are movable therewith, said cylinders being provided with inlet and exhaust ports both above and below the piston whereby the 115 motor may be actuated by fluid pressure 120
4. In a device of the character described, 125 the combination of a carrier vehicle, oppositely positioned supporting members provided with co-acting substantially vertical guide ways, a carrier bar transversely arranged and fitted to said guide ways, guide 130 shoulder elements provided on the carrier bar to engage the supporting members to prevent transverse shifting of the carrier bar, flanger deflecting plates supported upon the opposite ends of the carrier bar and positioned to operate adjacent to the rails, a supporting bar attached to the supporting members and positioned beneath the carrier bar to provide a lower stop bearing therefor, operating means for the carrier bar comprising oppositely positioned motors consisting of cylinder and piston members, said pistons being rigidly supported upon the supporting bar and said cylinders being movable with relation thereto and connected to the carrier bar whereby the latter and the flanger plates are movable therewith, said cylinders being provided with inlet and exhaust ports both above and below the piston whereby the 135 motor may be actuated by fluid pressure 140

- both to elevate and depress the flanger flanger plates, flexible conduits communicating with the respective cylinder ports and plates, flexible conduits communicating with the respective cylinder ports and compression springs fitted within the cylinder above the piston and operative normally to elevate the piston and operative normally to elevate the flanger plates into inoperative position and proportioned to be yieldable under the fluid pressure to permit of the latter operating to depress the flanger into position 65
- 10 for use, substantially as described.
4. In a device of the character described, the combination of a vehicle, oppositely positioned supporting members carried thereby, flanger plates suitably supported and 15 associated with the supporting members to be movable with relation thereto for elevating and depressing the flanger plates into and out of operative position, operating motors suitably supported at opposite sides of 20 the device, said motors having cylinder and piston members, one of said members being structurally rigid and the other movable with relation thereto, connections from the movable members to the flanger plates 25 whereby the latter are shifted into and out of operating position, said motors being adapted to be actuated by fluid pressure both to elevate and depress the flangers and compression springs interposed between the 30 respective rigid and movable members of the motor and operative normally to actuate the motor to elevate the flanger plates and said flanger plates being provided with inward extensions adapted to clear the full area between the rails.
5. In a device of the character described, the combination of a carrier vehicle, oppositely arranged supporting members provided with co-acting substantially vertical 40 guide ways, a carrier bar transversely arranged and fitted to said guide ways, guide shoulder elements provided on the carrier bar to engage the supporting members to prevent transverse shifting of the carrier 45 bar, flanger deflecting plates supported upon the opposite ends of the carrier bar and positioned to operate adjacent to the rails, a supporting bar attached to the supporting members and positioned beneath the carrier bar to provide a lower stop bearing therefor, operating means for the carrier bar 50 comprising oppositely positioned motors consisting of cylinder and piston members, said pistons being rigidly supported upon the supporting bar and said cylinders being 55 movable with relation thereto and connected to the carrier bar whereby the latter and the flanger plates are movable therewith, said cylinders being provided with inlet and ex- 60 haust ports both above and below the piston whereby the motor may be actuated by fluid pressure both to elevate and depress the
- flanger plates, flexible conduits communicating with the respective cylinder ports and a compression spring fitted within the cylinders above the piston and operative normally to elevate the flanger plates into inoperative position and proportioned to be yieldable under the fluid pressure to permit of the latter operating to depress the flanger 70 into position for use, and said flanger plates being provided with inward extensions adapted to clear the full area between the rails.
6. A snow removing device adapted for 75 attachment to a railway vehicle comprising oppositely positioned supporting members provided with guide ways arranged in angular relation, a carrier bar fitted to said guide ways and capable of substantially 80 vertical movement therein, a deflecting plate carried by the carrier bar and comprising flanger portions formed with notches to clear the rails and adapted to clear the snow immediately adjacent thereto and with an 85 intermediate plow portion to clear the area between the rails and said plate being inclined to deflect entirely to the one side and operating means therefor comprising motors situated at opposite sides of the vehicle, 90 said motors having movable members and connections therefrom to the carrier bar, said motor being adapted to be actuated by fluid pressures both to elevate and depress the carrier bar and compression springs incorporated in the motors to be operative 95 normally to elevate the carrier bar and deflecting plate into inoperative position, substantially as described.
7. In a snow removing device, the combination of a plow car having carriage trucks and a vehicle body supported thereon a main plow carried by the body and forwardly extending therefrom, a flanger snow deflecting plate suitably supported intermediate of the plow nosing portion and the forward truck and operating means therefor adapted to elevate and depress the flanger plates into inoperative and operative positions and a second flanger snow removing 100 device positioned to the rear of the forward truck and formed with a deflecting plate having flanger portions operative immediately adjacent the rails and with an intermediate plow portion to clear the full area between the rails, said deflecting plate being suitably inclined to deflect entirely to one side of the road bed and operating means therefor operative to elevate and depress the deflecting plate, substantially as 105 described.
- 110 In testimony whereof I have signed my name to this specification.
- 115 EBEN RAY PACKER.
